UNITED STATES PATENT OFFICE

2,596,249

BUBBLE TOWER

Frank J. Kerrigan, Winchester, Mass.

Application October 27, 1948, Serial No. 56,689

4 Claims. (Cl. 261—114)

1

This invention relates to improvements in bubble towers or fractionators which are gas-tight shells equipped with trays and having various pipe connections arranged in accordance with the particular process to be carried out.

Such bubble towers require bubble caps to be mounted on the trays and the bubble cap construction used in accordance with this invention may follow my prior Patent No. 2,320,822, granted June 1, 1943.

It is an object of my invention to make the trays and tray supports in sections that may be passed through the usual bubble tower manhole opening.

It is further an object of my invention to provide means for clamping the tray sections together by employing the posts or studs which mount the bubble caps, thereby eliminating the necessity of using other special fasteners.

It is further an object of my invention to use a plurality of hold-down straps around the bubble tower to clamp the trays, the straps being mounted for easy removal to replace the trays.

It is still further an object of my invention to provide means for clamping a plurality of bubble caps in position by straps fastened to the studs which mount the bubble caps.

Further objects and advantages of my improvements will be more readily apparent from the following description of preferred embodiments thereof as illustrated in the accompanying drawings, in which:

Figure 1 is a plan view of a bubble cap assembly;

Figure 2 is a vertical section of the bubble cap assembly taken on the plane indicated 2—2 in Figure 1;

Figure 3 is a horizontal section taken on the plane indicated 3—3 in section 2;

Figure 4 is a plan view of a modified construction for mounting bubble caps;

Figure 5 is a vertical section taken on the plane indicated 5—5 in Figure 4;

Figure 6 is a horizontal section taken on the plane 6—6 in Figure 5;

Figure 7 is a horizontal section taken through a bubble tower and showing the tray sections and bubble cap mountings;

Figure 8 is a fragmentary vertical section taken on the plane indicated 8—8 in Figure 7;

Figure 9 is a horizontal section taken through the bubble tower similar to Figure 7 but showing a modified construction;

Figure 10 is a fragmentary section taken on the plane 10—10 in Figure 9;

2

Figure 11 is an enlarged side elevation of a bubble cap assembly showing the tray sections in vertical section;

Figure 12 is a view similar to Figure 11 but showing a modified construction;

Figure 13 is a broken vertical section taken through the tray sections and showing the straps for clamping the trays to the bubble tower;

Figure 14 is a vertical sectional view taken on the plane 14—14 in Figure 7;

Figure 15 is a vertical sectional view taken on the plane 15—15 in Figure 9; and

Figure 16 is a fragmentary plan view showing a modified strap construction for clamping a plurality of bubble cap assemblies.

Figures 1, 2 and 3 illustrate the mounting of the bubble cap similar to that covered by Patent No. 2,320,822. The plate 10 has a circular opening to receive the cylindrical riser 12 which is inserted from the bottom of the plate and the riser 12 has a lip or collar 14 to engage the bottom of the plate around the circular opening. The riser 12 is held in position by the collar 16 which is turned to engage a lug on the riser. The collar 16 is forced upwardly with respect to the plate by the studs 18 which are threaded through the collar 16 and engage the top surface of the plate. The bubble cap 20 is mounted over the riser on the studs.

Figure 3 illustrates the manner in which the keys 22 on the collar 16 are free to slide vertically downward in the slots formed on the outer wall of the riser 12 whereupon the collar 16 may be turned to engage the keys beneath the lugs 24 on the riser. In this form of construction the riser is inserted from the bottom of the plate and the collar and bubble cap are assembled from above the plate.

Figures 4, 5 and 6 illustrate a modified construction in which the mounting of the riser and the bubble cap may be carried out from above the plate. In this construction, the plate 10 has an elliptical opening 26, the riser 28 is cylindrical and at its bottom has an elliptical flange 30 which will engage beneath the bottom of the plate when the riser is inserted from the top and then turned 90°. The dimensions are so designed that the riser may be tilted to slip the flange 30 beneath the plate and then the riser may be turned 90°. In its final position the flange 30 will close the opening 26 in the plate. The riser has the lugs 32 into which are threaded the studs 18 and the cap 20 is mounted in the same manner as in Figure 2.

Figures 7 and 8 show a bubble tower construc-

tion in which the cylindrical bubble tower 48 is provided with trays spaced vertically throughout the height of the tower. Each tray in Figure 7 comprises the sectional plates 42, 44 and 46. The tower has a shelf 48 around the shell on which the ends of the plates 42 and 44 rest. The tray section 42 may be reinforced by the ribs 50 while the tray section 44 is reinforced by the ribs 52. The sectional plate 46 has a vertical baffle 54 which forms the inlet weir. The downcomer 55 10 may be either permanently attached to the bubble tower as shown or removably attached by bolting to the tower. The downcomer has a shelf 57 to support the tray section 42 and also has a vertical extension 59 to form the overflow weir.

The bubble cap assemblies may be mounted on the plate, as shown in Figures 1, 2 and 3, or as in Figures 4, 5 and 6. Separate sealing plates 56 and 58 are used to cover the joints between the plate sections. The tray sections are held in place against the shelf 48 as shown in Figure 14. A number of pin bolts 60 are provided secured by nuts 62 to the shelf 48. The pin bolts 60 provide mountings for the hold-down bars 64. As shown in Figure 13, the hold-down bars 64 receive the compression screws 66 which bear against the plate sections 42 and 44 and against the sealing plate 56. The bars 64 are connected to the bolt pins 60 by the horizontal pins 68 which are retained in position by cotter pins 70. In order to remove the trays, it is only necessary to remove the cotter pins 70 and knock out each of the pins 68. This enables quick removal of the trays together with the bubble cap assemblies. The tray sections 35 are notched as at 61 to fit around the pin bolts 60.

Figure 11 shows the mounting of the bubble cap assembly in the bubble tower of Figure 7. The bubble cap is mounted at the joint between the plates 42 and 44, the joint being covered by the sealing plate 56. In this construction, the riser 12 is inserted from the bottom as in Figure 2 and the cap 20 is mounted on the studs 18. The bubble cap mounting serves to tie the plate sections 42 and 44 together and to hold the sealing plate 56 in position. If desired, as shown in Figure 11, the plates 42 and 44 may have a special anticorrosive sheet 70 on the underneath sides of the plates.

Instead of using the reinforcing ribs 50 and 52, a channel-shaped angle bar 72 may be mounted beneath the plates as in Figure 12. A bubble tower construction of this character is disclosed in Figures 9 and 10 in which the plate sections 74, 76 and 78 are mounted as shown in Figures 10 and 15 on a shelf support 80 welded to the tower 40. The joints between the plate sections are reinforced by the channel-shaped angle bars 72 and the bubble cap assemblies are mounted as shown in Figure 12.

In order to quickly remove the bubble cap covers, a plurality of caps 20 may be held down by a strap 82 which has the T-shaped heads 84 at its ends. The T-heads are fastened to the

studs 18 by cotter pins or other fastenings. The intermediate caps are held down on the studs by the strap and do not need to be fastened by cotter pins as in Figure 1.

I claim:

1. In a bubble tower, a mounting flange extending around the inside of the tower, a bubble tray composed of a plurality of sectional plates seated on said flange, a plurality of mounting posts on said flange, said sectional plates being freely removable from the bubble tower and means for holding the sectional plates into position comprising hold-down straps removably connected to the mounting posts, each of said straps having a plurality of compression screws to hold said plates down against said flange.

2. In a bubble tower, a shelf fixed to the inside wall of the tower, a plurality of plates to form a bubble tray resting on said shelf, a plurality of hold-down straps removably secured at their ends to the shelf, each of said straps having a plurality of screws bearing against the top side of said plates to hold said plates against said shelf, and a plurality of bubble cap assemblies mounted on and removable with each of said plates.

3. In a bubble tower, a plate having an elliptical opening therein, a cylindrical riser mounted in the opening, said riser having an elliptical flange at the lower end to seal the opening in the plate so that the flange may be pushed through the opening and the riser turned to a position where the flange obstructs the opening, a pair of studs threaded to the riser bearing against the plate to hold the riser in obstructing position and a bubble cap mounted over the upper end of the riser.

4. In a bubble tower, a plate having an elliptical opening, a riser adapted to be assembled in the elliptical opening of the plate in the top side of the plate, said riser having an eccentric elliptical flange in its lower end whereby the flange may be slipped through the opening in the plate by tilting the riser, the flange being designed to seal the opening in the plate when the riser is turned to its seated position and means engaging the top of the plate to force the riser upwardly.

FRANK J. KERRIGAN.
